UNITED STATES PATENT OFFICE.

GEORGE H. HULETT, OF CLEVELAND, OHIO, ASSIGNOR OF ONE-HALF TO
THE WEBSTER CAMP AND LANE COMPANY, OF AKRON, OHIO.

TROLLEY-WAGON.

SPECIFICATION forming part of Letters Patent No. 722,426, dated March 10, 1903.

Application filed July 11, 1902. Serial No. 115,226. (No model.)

To all whom it may concern:

Be it known that I, GEORGE H. HULETT, a resident of Cleveland, in the county of Cuyahoga and State of Ohio, have invented certain 5 new and useful Improvements in Trolley-Wagons; and I do hereby declare the following to be a full, clear, and exact description of the invention, such as will enable others skilled in the art to which it appertains to 10 make and use the same.

My invention relates to an improvement in trolley-wagons, the object of the invention being to provide an improved arrangement and mounting of hoisting, opening, and power 15 drums in the trolley-wagon to permit the operator in a cage suspended from the trolley to have entire control of the operation thereof, and, further, to provide improved mechanism whereby motion given the power-wheel by the 20 hoisting-cable is transmitted to the opening-rope drum, taking up the slack that would otherwise accumulate in the opening-rope as the bucket is hoisted.

With these objects in view the invention 25 consists in certain novel features of construction and combinations and arrangements of parts, as will be more fully hereinafter described, and pointed out in the claims.

In the accompanying drawings, Figure 1 is 30 a side view illustrating my improvements. Figs. 2 and 3 are enlarged detail views of the trolley-wagon. Fig. 4 is an end view on a small scale, showing the application of my invention, the relation of the various features 35 to each other being shown diagrammatically.

1 represents a bridge or frame provided with tracks 2, on which run wheels or rollers 3, carried by my improved trolley-wagon 4. The wagon 4 comprises a metal frame, a portion 40 of which is made in the form of a cage or cab 5 for the operator, and the operating-drums are all mounted upon a single shaft 6, supported in the frame. On this shaft 6 is provided a power wheel or drum 7, keyed thereto, and on this same shaft are keyed one or more spools or small drums 8, to which the closing and hoisting cables 8^a are attached. A cable 7^a from the hoist-drum in the machinery-tower passes around and is secured to 45 the power-wheel 7.

Loosely mounted on the shaft 6 is the open-

ing-rope drum 9, and the lower end of opening-ropes 10 are fastened to the frame of an ordinary clam-shell bucket 11. The bucket illustrated is what is known as the "Hulett" 55 bucket, and the end of the opening-rope is attached to chains or cables passing around the opening quadrants of the bucket; but it is not essential to employ this particular construction of bucket, as others may be used in which 60 the weight of the bucket in opening is thrown upon the opening-rope to open the same.

A brake-disk 12 is secured to the opening-drum 9 and frictionally engaged by a brake-band 12^a through the medium of a hand or 65 foot lever 13 to hold the disk 12 against movement, thus holding the bucket suspended in any position desired, as will hereinafter appear. A friction-clutch 14 also engages this disk 12 to lock the same to the shaft 6, and 70 any approved mechanism may be provided for operating this friction-clutch.

To move the trolley along the tracks, the motor could be located in the trolley-wagon, but preferably in a machinery-house. If located in the machinery-house, a drum would be provided with one cable 15 wound around this drum and attached to the same, the opposite end being carried over suitable sheaves and attached to the trolley-frame. Another 75 cable 16 is wound around the same drum, but in the opposite direction, is passed over suitable sheaves, and attached to the opposite end of the trolley-frame.

The operation of my improvements is as 85 follows: To operate the excavating-bucket, the trolley, with the bucket suspended, is run over the material to be hoisted. By applying the hand or foot lever 13 to the disk 12 and releasing friction-clutch 14 the opening-drum 9 will be securely held and the weight 90 of the bucket in lowering revolves power-wheel 7 backward, unwinding the ropes from the hoisting spools or drums 8 and winding the rope 7^a on the power-wheel. In turn the 95 winding of the rope 7^a on the power-wheel 7 draws the hoist-drum in the machinery-tower backward, the bucket being opened and the hand or foot lever 13 released, the bucket descending open into the material to be hoisted. 100 To close and hoist the bucket, the motor in the machinery-house is started, winding up

the power-cable 7^a to turn the power-wheel 7, hoisting-drum 8, and draw up hoisting-cables 8^a to close the bucket and inclose the material. As soon as the bucket is closed the friction-clutch 14 is thrown into engagement by the operator in the cab or cage, and hence locking the opening-drum 9 to shaft 6 and compelling it to turn to wind the opening-rope 10 thereon as the power-wheel 7 and hoisting-drums 8 are turned. Continuing the motion in the same direction, the bucket is raised to the height desired, when lever 13 is operated to hold the bucket in such position. The motor-drum in the machinery-house is now operated, and through the medium of cables 15 and 16 moves the trolley anywhere on the tracks 2, the power-cable 7^a being wound upon or unwound from power-wheel 7, according to the direction of movement of the trolley. 20 A great many changes might be made in the general form and arrangement of the parts described without departing from my invention, and hence I would have it understood that I do not limit myself to the precise construction set forth, but consider myself at liberty to make such slight changes and alterations as fairly fall within the spirit and scope of my invention.

Having fully described my invention, what 30 I claim as new, and desire to secure by Letters Patent, is—

1. The combination with a trolley-wagon and a shaft thereon, of a power-wheel keyed

to the shaft, a hoisting-drum keyed to the shaft, an opening-drum loose on the shaft, 35 means for locking the opening-drum to the shaft, a brake to hold the opening-drum and shaft against turning and an operating-cable wound on the power-wheel and extending beyond the trolley to be operated by distant 40 mechanism.

2. The combination with a trolley-wagon, of a shaft mounted to revolve in said frame, a power-wheel keyed to said shaft, a hoisting-drum keyed to the shaft, an opening-drum 45 loose on the shaft, a friction-disk secured to the opening-drum, a brake to engage the disk, a friction-clutch to lock the disk and shaft together, means in the trolley-wagon for operating said brake and clutch, and a cable for 50 rotating the power-wheel.

3. The combination with an elevated track and a trolley-frame thereon, of hoisting and opening drums in said frame, hauling-cables connected to opposite sides of the trolley-frame, a cab or cage on the frame and means controlled by the operator in the cab or cage for controlling the entire operation of the opening-drum. 55

In testimony whereof I have signed this 60 specification in the presence of two subscribing witnesses.

GEORGE H. HULETT.
